UNITED STATES PATENT OFFICE.

CHARLES A. B. SCHNURR, OF BROOKLYN, NEW YORK.

CAPTIVE BALL FOR GOLF-PRACTICE.

1,326,976.

Specification of Letters Patent.

Patented Jan. 6, 1920.

Application filed April 19, 1918. Serial No. 229,519.

To all whom it may concern:

Be it known that I, CHARLES A. B. SCHNURR, a citizen of the United States, and a resident of Brooklyn, in the county of 5 Kings and State of New York, have invented certain new and useful Improvements in Captive Balls for Golf-Practice, of which the following is a full, clear, and exact description, whereby any one skilled in the art 10 may make and use the same.

The invention relates to a device to be used for practising and perfecting the stroke and stance of a golf-player, and more particularly to a "tethered" ball and a means 15 of arranging the tether to give a natural and perfect freedom of movement to the ball.

The object of the invention is to provide a device which may be used by a golf-player for practice purposes to aid him in training 20 the eye and securing accuracy in his strokes. More specifically, the object of the invention is to provide a "tethered" ball which may be driven from the "tee" and which will take a natural and perfect line of flight, returning 25 within easy reach of the player.

Further objects of the invention relative to the arrangement of the several elements and their securing means are hereinafter more particularly described and set forth in 30 the claims.

Referring to the drawings:

Figure 1 is an illustrative view showing the tethered ball upon the tee.

Fig. 2 illustrates the ball near the end of 35 its flight.

Fig. 3 illustrates the ball returned after its flight.

Fig. 4 is a detail view illustrating the several elements of the tether.

Fig. 5 is a sectional view through the ball with attached buffer-member.

Fig. 5^a indicates a means of securing the buffer-member and tethering cord.

Fig. 6 is a sectional view showing a modified means of anchoring the attaching eye for the tethering cord.

Fig. 7 illustrates a preferred method of attaching the buffer-member and tethering cord.

Fig. 8 illustrates the straight pull knot for tying in the tethering cord.

Golf-players ordinarily, in entering a game of golf, find it desirable to "warm up" and practice various strokes. Usually, this

55 requires the use of a caddie and a great loss of time in returning the ball to the tee.

Captive golf balls are not new in the art as many devices have been used for providing practice for the player. These ordinarily, so far as known to applicant, have consisted of balls tethered to pivoted pins in such manner that the player places the ball between himself and the pin, with the tether extending radially. Upon striking the ball, it revolves about the pin or pivotal point of 60 the tether and does not fly forward in the natural line of flight which the ball would take if untethered.

As hereinafter set forth, the present invention is designed to permit the player to 70 observe the effect of his strokes upon the ball, said ball returning to the player after it has been driven from the tee. The device also permits the use of any of the strokes required under different conditions and with 75 or without a tee.

A niblick, mashy, brassy, or driver stroke may be played with equal facility.

In the accompanying drawings, B, denotes the ball which may be of any desired type 80 and to which is secured an eye or fastening device 1. This, as illustrated in Fig. 5, consists of a screw-eye having a coarse pitched thread which is screwed directly into the substance of the ball and secures a firm hold 85 therein. There is a countersunk opening 2, which receives the eye and permits the attachment of a buffer member or strap 3. The countersunk opening is sufficiently deep to permit insertion of the eye within the peripheral surface of the ball. The buffer 3, is preferably formed of rawhide and is in the form of a loop having perforations 4, 5, at its ends. It is important a buffer-strap of resilient, though tough and non-stretching, material be employed inasmuch as the ball, upon striking the ground after being driven, tends to turn back upon the tether and would cut out a cord, wire, or in fact 90 any material, except rawhide or a like 95 leather.

The tether cord 6, has a comparatively long loop at one end as at 7, which may be passed through the perforations 4, 5, of the buffer-strap 3, and passed over the ball to 100 form a slip loop connection, as illustrated in Figs. 5, 5^a.

A preferred arrangement of the buffer-strap and tethering loop is illustrated in Fig. 7, where the end of the loop 8, after 110 being drawn through the perforations 9, 10, is passed back over the cords 11, 12, of the

main loop and then passed over the ball and its attached buffer-strap 3. This provides a straight pull knot, as illustrated in the detail view of Fig. 7, the loop 8, pulling snugly 5 about the cords 11, 12, and snugging about the ends of the buffer member 3, above the perforations 9, 10.

In Fig. 8, there is illustrated a form of knot which is preferably employed in making 10 the loop 7. This is what might be termed a "straight pull" or "leader" knot and insures a maximum pull with minimum liability of breakage of the cord.

The opposite end of the cord from the 15 buffer-strap is formed into a loop 13, which is formed with a "leader" knot, said loop being passed about a coöperating loop 14, formed at the end of an elastic strip 15.

The opposite end of the elastic strip 15, is 20 provided with a loop 16, which passes through the eye 17, of the tethering pin 18.

The elastic loops 14, 16, are preferably secured by clips 19, of any well known type.

It will be observed that there is a buffer- 25 strip or thong next to the ball, for taking the blow of the ball; a comparatively long light tethering cord, extending from said buffer-thong to the elastic section 15; and a comparatively short elastic section.

30 The disposition of the buffer strips or thong, the tethering cord, and the elastic medium is important. Where an attempt has been made to use a connecting tether direct to a ball without the buffer-strip described, 35 the device is extremely short-lived, inasmuch as the back throw of the ball on the ground cuts the tether. With the arrangement disclosed, the buffer-strip or thong is passed through the attaching eye of the ball and its 40 end from a flexible attaching means for the tethering cord so that there are no cutting strains imposed upon the cord.

The disposition of the elastic section at 45 the opposite end of the tether and secured to the tethering pin 18, also provides a resilient connecting loop for the opposite end of the tethering cord and disposes the somewhat heavy resilient section adjacent to the tethering pin, where it will re-act to return the ball only after the lighter parts have taken 50 their full flights.

This arrangement provides a very light cord to be carried by the ball for a considerable distance, with a resilient member to 55 gradually absorb the shock as the ball tightens the cord, and providing a return spring which will bring the ball back within reach of the player.

In use, the tethering pin 18, is forced into 60 the ground and the ball is carried back from the pin to the tee, as illustrated in Fig. 1.

Whether the player drives from the tee with his driver or uses a stroke employing various other clubs, irons, etc., he faces the 65 ball at right angles to the line of the tether.

It follows that the line of flight of the ball will be over the tethering pin rather than about it, and the ball will take its natural line of flight as though not tethered. This gives the player practice in sighting his ball 70 and permits him to correct inaccuracies of his stroke. It is obvious that he can employ any of the strokes required with the different clubs. This has been quite impossible with devices where the ball has been 75 driven about the tethering pin as, of course, there was practically no natural flight permitted for the ball.

By utilizing a light cord of considerable length, a considerable flight may be permitted 80 to the ball. This may be increased or diminished as desired. Of course, the distance of flight will be approximately double the length of the tether. The elastic member may be of rubber, spring, or other elastic 85 material, its whole function being to absorb the shock due to the pull of the ball on the cord, to prevent breaking of the cord; and to give a sufficient back pull to cause the ball to roll back within reach of the user. 90

In Fig. 6, there is illustrated a modified arrangement of eye for securing a buffer-thong. In this case, the ball *a*, has a short shank *b*, with an eye *c*, and enlarged mushroom end or anchor *d*, molded directly into 95 the material of the ball. There is a countersunk opening *e*, about the eye to prevent chafing of the thong. It is, of course, quite immaterial how the eye is anchored in the ball so long as it is inserted with a holding 100 means sufficient to withstand the pull of the tether.

What I claim as my invention and desire to secure by Letters Patent is:

1. A captive golf ball device consisting of 105 a golf ball with means for attachment of a tether, a tether and a tethering pin, said tether comprising a comparatively long section of light cord and a comparatively short section of resilient material flexibly joined 110 together, a thong connecting the light cord with the ball and the resilient material connecting the cord with the tethering pin, whereby the ball may be driven in a natural line of flight across the tethering pin 115 through a distance substantially twice as long as the tether.

2. A captive golf ball device consisting of 120 a ball, an eye having a shank secured in the ball, a recess in the ball to receive the eye, a tethering pin, a tether connected with the eye and tethering pin and comprising a thong engaging the eye, a cord engaging the thong, and a resilient member engaging the cord and tethering pin.

3. A captive golf ball device consisting of 125 a ball, an eye having a shank secured in the ball, a recess in the ball to receive the eye, a thong passing through the eye and having its ends united with a tethering cord, a 130

resilient member connected with the opposite end of the tethering cord, and a tethering pin connected with the resilient member.

4. In a device of the character described, 5 a ball having means for securing a tether, a thong connected with said means, a tethering cord connected with said thong, a tethering pin, and a resilient member connecting the tethering pin and tethering cord.
- 10 5. A tether for a captive golf ball consisting of a rawhide thong in the form of a loop having perforations in its ends, a cord having a loop extending through said perforations and secured about the ends of the 15 thong, an elastic member secured to the opposite end of said cord, a tethering pin for

holding said tether, and a golf ball having means for the attachment thereto of the rawhide thong.

6. In a device of the character described, 20 a tether for a golf ball comprising a rawhide thong section, a comparatively long cord member and a comparatively short resilient member, said members joined together by loops, said thong being attached to the golf 25 ball and said resilient member being attached to the tethering pin.
